UNITED STATES PATENT OFFICE.

INGEBRET BÖHN, OF SÖRUMSAND, NORWAY.

ROCK-DRILLING MACHINE.

1,369,609.

Specification of Letters Patent. Patented Feb. 22, 1921.

Application filed May 20, 1919. Serial No. 298,514.

To all whom it may concern:

Be it known that I, INGEBRET BÖHN, a subject of the King of Norway, residing at Sörumsand, Norway, have invented certain new and useful Improvements in Rock-Drilling Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention has for its object to provide a rock drilling machine of the type described in applicant's previous U. S. application for patent Serial No. 205369. The principal new feature of the present invention consists in the driving mechanism for the reciprocating rock drills, which are mounted on a rotating disk at the front end of the machine.

20 According to the present invention the rock drills receive their reciprocating movement from the rotating crank at the front end of a central shaft.

25 A form of the invention is diagrammatically illustrated by an axial section on the drawing.

The machine is driven from the electric motor 16 if necessary by means of gears or the like. Shaft 9 is provided with a crank bearing 8 and a crank disk 7 carrying a 30 crank pin 6. The crank pin 6 is connected by means of rods 5 to T-levers 4, which are pivoted at their apex on a disk 12 and are given an oscillating movement by means of the crank pin 6. There is sufficient loose-

ness in the joints of the pivotal connection 40 of the rods 5 to permit slight lateral movement thereof. By the oscillations of the T-levers 4 the rock drills 1, which are connected to the free ends of the T-levers, are given a reciprocating movement. Links 2 45 pivoted at the front end of projecting arms 3 serve to guide the rock drills in their movement, and an annular sleeve or projecting flange 13 serves to protect the mechanism against falling rocks or the like. The front disk 12 is fastened to a cylinder or 50 drum 10, which is journaled in sleeve 11 mounted on the machine frame, and the said cylinder or drum 10 is given a slow rotating movement from motor 16 by means of 55 gears 14, 15.

The operation of the machine is exactly similar to the operation of the machine described in applicant's above named application, the feeding movement taking place by 60 driving the carrying wheels from the motor 16.

Claim—

In a rock drilling machine, a plurality of reciprocating drills, a central rotary shaft, 65 a crank at the front end of the latter, a plurality of pivoted T-levers loosely articulated to said crank, and means connecting the free ends of the T-levers to the drills whereby the latter are reciprocated.

In testimony that I claim the foregoing as my invention, I have signed my name in presence of two subscribing witnesses.

INGEBRET BÖHN.

Witnesses:

A. HEDENCHON,
MARGARET BUGGE.
